OXIDATION OF HYDROCARBONS

Meinhard H. Kotzebue, Houston, Tex., assignor
to Celanese Corporation of America, a corpora-
tion of Delaware

Application October 16, 1947, Serial No. 780,137

10 Claims. (Cl. 260—451)

1

This invention relates to a process for the production of oxygenated organic compounds and relates more particularly to an improved process for the production of organic compounds by the oxygenation of hydrocarbons in a highly efficient and economical manner.

In the partial oxidation of aromatic, cycloaliphatic and aliphatic hydrocarbons, such as propane and butane, for example, at elevated temperature and pressure with the aid of a controlled amount of air, products such as acetaldehyde, formaldehyde, propionaldehyde, acetone, acetic acid and other organic compounds such as methyl, ethyl and propyl alcohol are produced. The use of elevated temperature and pressure produces a partial cracking of the hydrocarbons and, while in the resulting unstable state, the cracked hydrocarbons combine with oxygen in an exothermic reaction. The oxygenated reaction mixture obtained normally contains some unreacted hydrocarbon since the amount of air employed is limited to avoid the formation of lean mixtures low in hydrocarbon content. Such lean mixtures not only create a possible explosion hazard due to excessively rapid and uncontrollable temperature rise but also favor the complete oxidation of the hydrocarbons to coke, resins and carbon dioxide rather than a limited oxidation to the desired oxygenated compounds. The unreacted hydrocarbon must, of course, be recovered and recycled in the process in order to render the same commercially feasible. However, recovery and recycling is costly since hydrocarbon recovery must be effected under high pressures. Accordingly, effecting the oxidation in a manner which produces as great a conversion of the hydrocarbons as possible to oxygenated organic compounds and, in addition, a reduction in the cost of the hydrocarbon recovery is obviously, a substantial step forward in the art.

It is, therefore, an important object of this invention to provide an improved process for effecting the partial oxidation of hydrocarbons to form oxygenated organic compounds whereby said reaction is carried out in stages whereby the amount of hydrocarbon oxidized per pass to commercially valuable products is greatly increased.

Another object of this invention is to carry out said hydrocarbon oxygenation by simultaneously effecting a partial cracking of the hydrocarbons undergoing reaction.

A further object of this invention is the provision of a hydrocarbon oxygenation process wherein unreacted hydrocarbons are recovered under pressure in an economical and efficient manner and substantially complete utilization of

2

the potential energy of the compressed hydrocarbons and unreacted inert gases in the reaction system is achieved.

Other objects of this invention will appear from the following detailed description and accompanying drawing.

The accompanying drawing comprises a diagrammatic flow-sheet for carrying out the novel process of my invention.

In accordance with my novel process, I have found that the partial oxidation of hydrocarbons in the gaseous phase to form oxygenated organic compounds may be effected with a more efficient conversion per pass of hydrocarbon to oxygenated organic compounds if the oxidation is effected in two stages. The initial oxidation is preferably effected with only sufficient air present so that the endothermic cracking and exothermic partial oxidation reactions taking place will maintain the temperature at from about 600 to 900° F. and the secondary oxidation effected with oxygen at a temperature of about 900 to 1250° F. followed by rapid cooling. The amount of oxygen added for the second stage is so controlled that the temperature is not permitted to rise substantially beyond this range. The secondary oxidation not only acts to oxygenate part of the unreacted hydrocarbon but also acts simultaneously to further crack a part of the unreacted hydrocarbons present and thus render further oxygenation of the unreacted hydrocarbons to oxygenated compounds during this secondary oxidation more complete. The oxygenation reactions are preferably effected under pressures of 75 to 200 pounds per square inch gauge, the pressure employed depending upon the particular hydrocarbon or hydrocarbon mixture undergoing oxidation and the type of oxygenated products desired.

The gaseous reaction products leaving the reaction zone following the secondary oxidation are immediately cooled to between about 300 to 500° F. to halt further reaction and the tars and resins present are then removed in a suitable scrubber. The scrubbed reaction gases are cooled further to between 100 to 200° F., passed through a second scrubber where the high-boiling products are removed, and then passed through a water absorber to remove the water-soluble oxidation products such as aldehydes, acids, ketones, etc. The gaseous portion which remains after the products are removed comprises cracked, aromatic or unsaturated hydrocarbons, light hydrocarbons and inert gas, such as nitrogen, which enters with the air fed to the system to effect the initial oxidation. The cracked, aromatic and

unsaturated hydrocarbons are removed from the gases by being absorbed in a suitable solvent such as kerosene or mineral seal oil, preferably with some diethylene glycol present to remove any water vapor. These hydrocarbons may be stripped from the solvent and recycled to the system in whole or in part or subjected to a separate, further oxygenation. The remaining gaseous mixture comprises the valuable unreacted light hydrocarbons and the inert gas.

Even though my novel oxidation process effects a large increase in the proportion of hydrocarbon oxidized per pass, the unreacted light hydrocarbons remaining still comprise a substantial fraction of the original hydrocarbon feed to the system, and these light hydrocarbons must be recovered. However, the light hydrocarbons boil at very low temperatures and can only be recovered efficiently by solvent absorption under pressures of 600 to 1200 pounds per square inch gauge employing very low temperatures of the order of -100 to -40° F.

Accordingly, the mixture of light hydrocarbons and inert gases is compressed by a suitable compressor to the necessary absorption pressure and, after being sufficiently cooled, the mixture is passed through an absorber where the hydrocarbon components are absorbed in a suitable organic solvent, the unabsorbed inert gases preferably passing upward therein countercurrent to the flow of the absorbing solvent. The absorber solvent is then stripped of the absorbent hydrocarbons and the latter recycled to the oxidation zone, the solvent being again chilled and again circulated through the absorber.

Since the hydrocarbon absorption requires considerable refrigeration in order to effect the removal of the hydrocarbons from the inert gases in an efficient manner at the necessary low temperature, a suitable refrigeration system requiring a considerable power input must be provided. However, the inert gases leaving the hydrocarbon absorber are under rather high pressures and lower than normal temperatures and it is, therefore, an important feature of my novel process to utilize the energy in the inert gases to provide the desired refrigeration as well as to provide the relatively pure oxygen which is employed in effecting the secondary oxidation reaction in my process described above.

Thus, in order to utilize the potential energy contained therein, the inert gases under pressure are allowed to pass through an expander operatively connected to an air compressor. The expansion of and the work performed by the inert gases greatly reduces their temperature while at the same time their expansion causes the air compressor to boost the air from atmospheric pressure to a pressure of 100 to 300 pounds per square inch. The compressed air is then chilled by employing as a refrigerant the low temperature inert gas, and the compressed air is thus liquefied. The liquid air obtained is then fractionated, with the oxygen going to the secondary oxidation reaction zone. The nitrogen which is distilled off is circulated through the system where necessary to provide additional refrigeration to aid in liquefying the compressed air and to aid in chilling the hydrocarbon gas absorption solvent and in chilling the light hydrocarbon gas absorber.

Referring now to the drawing wherein there is shown a preferred embodiment of apparatus for carrying out the novel process of my invention, the gaseous hydrocarbons to be oxidized enter a reactor 1 under pressure through an inlet

line 2 which passes through a heat exchanger 3 where said gases are preheated. The preheated hydrocarbon gases pass upward in the reactor 1 and meet a stream of air entering through an inlet 4. The amount of air relative to the entering hydrocarbon is closely controlled. The initial oxidation reaction takes place in a reaction zone comprising a tube 5 and the gaseous reaction mixture leaves reactor 1 and reaction tube 5 through a product discharge outlet 5'. The oxygen in the reacting mixture is partially consumed by the time the reaction gases reach discharge outlet 5' and the nitrogen present acts as a retarding agent. To effect the desired secondary reaction, oxygen is admitted to outlet 5' through a pipe 6 in an amount controlling the temperature rise desired. The secondary oxidation reaction takes place in a suitable mixing chamber 6' and, following the secondary reaction, the reaction mixture produced is immediately cooled below reaction temperature in heat exchanger 3 by the cooling effect of the entering hydrocarbon gas feed moving countercurrently to the flow of the reaction gases. The cooled reaction gases then pass to a scrubber 7 which is held at a sufficiently high temperature to permit removal of any tars and resins produced while the latter are in a liquid form. The temperature of the gaseous reaction mixture is cooled further in cooler 8 and excess high boiling products are removed in a scrubber 9.

The gaseous reaction mixture now remaining is then passed upward through an absorber 10 countercurrent to a stream of water entering through an inlet 11 and the water-soluble compounds present are removed, the aqueous solution of water-soluble products which forms being discharged through a line 12 at the base of absorber 10. The temperature in absorber 10 is controlled by an internal cooling coil 13. After removal of the water-soluble products the gaseous reaction mixture is then passed through a conduit 14 into a second absorber 15 where the cracked, aromatic or unsaturated hydrocarbon gases are removed employing a suitable solvent, which preferably contains some diethylene glycol to ensure the removal of any water and prevent precipitation of the same in the form of ice when the gases are subsequently cooled. The solvent 50 enters absorber 15 through a line 16 and flows downwardly in the absorber. The solution formed is discharged at the base of absorber 15 through a discharge pipe 17. The absorbed hydrocarbons may be stripped from the solvent and 55 may be oxygenated at low pressure and temperature with the aid of suitable catalysts or may be recycled to reactor 1 in whole or in part. The unabsorbed gases now remaining consist of light hydrocarbons and inert gas, such as nitrogen.

In order that the process be economically feasible, as stated above, the light hydrocarbons must be recovered, and solvent absorption at low temperatures and high pressures offers the most efficient means for recovery of these light hydrocarbons.

Accordingly, the gaseous mixture of light hydrocarbons and inert gas is fed through a conduit 18 to a compressor 19 where the pressure is boosted to 600 to 1200 pounds per square inch. The temperature of the gases rises considerably when compressed and the temperature is substantially reduced by means of coolers 20 and 21, a suitable cooling medium being employed, which medium is passed through pipe 22. The cooled, compressed gases pass through line 23 into absorber

24 and the light hydrocarbons are absorbed by a stream of cold oil entering absorber 24 through an inlet 25. The absorber oil is chilled in cooler 26 prior to entering absorber 24 and the temperature in said absorber 24 is maintained at the desired low level by the action of a cooling coil 27. The cold oil solution of light hydrocarbons formed leaves absorber 24 through a discharge pipe 28 and is circulated through cooler 21 to reduce the temperature of the compressed gaseous mixture entering absorber 24 to be stripped of its light hydrocarbon content. The oil solution of light hydrocarbons leaves cooler 21 through pipe 29 and may be stripped of the light hydrocarbons in a suitable stripping still (not shown) and the absorber oil recycled through cooler 26 to absorber 24 to absorb additional light hydrocarbons.

The chilled, unabsorbed inert nitrogen gas comes overhead from absorber 24 through a line 30 under high pressure and is passed through an expander 31. The expansion of the inert nitrogen gas drives an air compressor 32 which draws air in through a line 33 provided with a filter 3. The compressed air passes through an after-cooler 35 through a line 36 provided with a suitable circulating refrigerant, and the chilled air then scrubbed and dehydrated in a scrubber 37. The cooled scrubbed and dehydrated compressed air is then liquefied in heat exchanger 38 by the cold, expanded nitrogen gases leaving expander 31. The nitrogen gas is at a temperature of -350 to -250° F. after expansion, at which temperature air at 100 to 300 pounds per square inch gauge may be readily liquefied. The cold nitrogen enters heat exchanger 38 through a pipe 39 and after liquefying the air is passed through cooling coil 27.

The liquid air produced enters fractionating still 40 through a line 41 where the nitrogen is distilled off overhead. The nitrogen is piped to heat exchanger 38 through line 42 where it serves to aid in the liquefaction of the compressed air. The purified liquid oxygen is removed from the base of still 40 through line 43. The oxygen may be employed directly for the secondary oxidation reaction or may be employed to provide any necessary refrigeration in the system prior to being passed to the oxygenation reaction.

My novel process enables the oxidation of hydrocarbons to valuable products to be conducted efficiently with reduced equipment costs, minimizes expensive heating and cooling operations and reduces the amount of by-products in the effluent gases which are not economical to recover.

It is to be understood that the foregoing detailed description is given merely by way of illustration and that many variations may be made therein without departing from the spirit of my invention.

Having described my invention, what I desire to secure by Letters Patent is:

1. In a process for the partial oxidation of hydrocarbons in the vapor phase at elevated temperature and pressure to form oxygenated organic compounds, the steps which comprise subjecting the hydrocarbons to an initial partial oxidation with oxygen containing an inert gaseous diluent under such conditions that a temperature of 600 to 900° F. is developed and maintained and then subjecting the gaseous reaction mixture obtained to further oxidation with added oxygen free of any inert diluent, said

further oxidation producing a temperature higher than that of the initial partial oxidation reaction whereby both a partial cracking of unreacted hydrocarbons present and the formation of additional oxygenated organic compounds is effected.

2. In a process for the partial oxidation of hydrocarbons in the vapor phase at elevated temperature and pressure to form oxygenated organic compounds, the steps which comprise subjecting the hydrocarbons to an initial partial oxidation with oxygen containing an inert gaseous diluent at a temperature of 600 to 900° F. and then subjecting the gaseous reaction mixture obtained to further oxidation with added oxygen free of any inert diluent, said further oxidation producing a temperature higher than that of the initial partial oxidation reaction whereby both a partial cracking of unreacted hydrocarbons present and the formation of additional oxygenated organic compounds is effected.

3. In a process for the partial oxidation of hydrocarbons in the vapor phase at elevated temperature and pressure to form oxygenated organic compounds, the steps which comprise subjecting the hydrocarbons to an initial partial oxidation with oxygen containing an inert gaseous diluent at a temperature of 600 to 900° F. and then subjecting the gaseous reaction mixture obtained to further oxidation with added oxygen free of any inert diluent, said further oxidation producing a temperature of 900 to 1250° F. whereby both a partial cracking of unreacted hydrocarbons present and the formation of additional oxygenated organic compounds is effected.

4. In a process for the partial oxidation of hydrocarbons in the vapor phase at elevated temperature and pressure to form oxygenated organic compounds, the steps which comprise subjecting the hydrocarbons to an initial partial oxidation with oxygen containing an inert gaseous diluent at a temperature of 600 to 900° F. and a pressure of 75 to 200 pounds per square inch gauge and then subjecting the gaseous reaction mixture obtained to further oxidation with added oxygen free of any inert diluent, said further oxidation producing a temperature of 900 to 1250° F. whereby both a partial cracking of unreacted hydrocarbons present and the formation of additional oxygenated organic compounds is effected.

5. In a process for the partial oxidation of hydrocarbons in the vapor phase at elevated temperature and pressure to form oxygenated organic compounds, the steps which comprise subjecting the hydrocarbons to an initial partial oxidation with oxygen containing nitrogen as an inert gaseous diluent at a temperature of 600 to 900° F. and a pressure of 75 to 200 pounds per square inch gauge and then subjecting the gaseous reaction mixture obtained to further oxidation with added oxygen free of any inert diluent, said further oxidation producing a temperature of 900 to 1250° F. whereby both a partial cracking of unreacted hydrocarbons present and the formation of additional oxygenated organic compounds is effected.

6. Process for the partial oxidation of hydrocarbons in the vapor phase at elevated temperature and pressure to form oxygenated organic compounds, which comprises subjecting the hydrocarbons to an initial partial oxidation in a reaction zone with oxygen containing an inert gaseous diluent under such conditions that a

temperature of 600 to 900° F. is developed and maintained, subjecting the gaseous reaction mixture obtained to further oxidation with added oxygen free of any inert diluent, said further oxidation producing a temperature higher than that of the initial partial oxidation reaction whereby both a partial cracking of unreacted hydrocarbons present and the formation of additional oxygenated organic compounds is effected, separating the oxygenated organic compounds from the reaction gases, separating the unreacted light hydrocarbons from the inert gaseous diluent present by absorption under pressure with the aid of a liquid solvent, expanding the unabsorbed inert gaseous diluent to lower the temperature of the same and simultaneously to compress air, cooling and liquefying the compressed air with the aid of the cooled, expanded inert gaseous diluent, separating the oxygen from the liquefied air and cycling it to the oxidation reaction zone to effect further oxidation of the partially oxidized hydrocarbon mixture, and cycling the cooled nitrogen separated from the liquefied air to supply necessary refrigeration to the reaction system.

7. Process for the partial oxidation of hydrocarbons in the vapor phase at elevated temperature and pressure to form oxygenated organic compounds, which comprises subjecting the hydrocarbons to an initial partial oxidation in a reaction zone with oxygen containing an inert gaseous diluent at a temperature of 600 to 900° F., subjecting the gaseous reaction mixture obtained to further oxidation with added oxygen free of any inert diluent, said further oxidation producing a temperature higher than that of the initial partial oxidation reaction whereby both a partial cracking of unreacted hydrocarbons present and the formation of additional oxygenated organic compounds is effected, separating the oxygenated organic compounds from the reaction gases, separating the unreacted light hydrocarbons from the inert gaseous diluent present by absorption under pressure with the aid of a liquid solvent, expanding the unabsorbed inert gaseous diluent to lower the temperature of the same and simultaneously to compress air, cooling and liquefying the compressed air with the aid of the cooled, expanded inert gaseous diluent, separating the oxygen from the liquefied air and cycling it to the oxidation reaction zone to effect further oxidation of the partially oxidized hydrocarbon mixture, and cycling the cooled nitrogen separated from the liquefied air to supply necessary refrigeration to the reaction system.

8. Process for the partial oxidation of hydrocarbons in the vapor phase at elevated temperature and pressure to form oxygenated organic compounds, which comprises subjecting the hydrocarbons to an initial partial oxidation in a reaction zone with oxygen containing an inert gaseous diluent at a temperature of 600 to 900° F., subjecting the gaseous reaction mixture obtained to further oxidation with added oxygen free of any inert diluent, said further oxidation producing a temperature of 900 to 1200° F. whereby both a partial cracking of unreacted hydrocarbons present and the formation of additional oxygenated organic compounds is effected, separating the oxygenated organic compounds from the reaction gases, separating the unreacted light hydrocarbons from the inert gaseous diluent present by absorption under pressure with the aid of a liquid solvent, expanding the unabsorbed inert gaseous diluent to lower the

temperature of the same and simultaneously to compress air, cooling and liquefying the compressed air with the aid of the cooled, expanded inert gaseous diluent, separating the oxygen from the liquefied air and cycling it to the oxidation reaction zone to effect further oxidation of the partially oxidized hydrocarbon mixture, and cycling the cooled nitrogen separated from the liquefied air to supply necessary refrigeration to the reaction system.

9. Process for the partial oxidation of hydrocarbons in the vapor phase at elevated temperature and pressure to form oxygenated organic compounds, which comprises subjecting the hydrocarbons to an initial partial oxidation in a reaction zone with oxygen containing an inert gaseous diluent at a temperature of 600 to 900° F. and a pressure of 75 to 200 pounds per square inch gauge, subjecting the gaseous reaction mixture obtained to further oxidation with added oxygen free of any inert diluent, said further oxidation producing a temperature of 900 to 1200° F. whereby both a partial cracking of unreacted hydrocarbons present and the formation of additional oxygenated organic compounds is effected, separating the oxygenated organic compounds from the reaction gases, separating the unreacted light hydrocarbons from the inert gaseous diluent present by absorption under pressure with the aid of a liquid solvent, expanding the unabsorbed inert gaseous diluent to lower the temperature of the same and simultaneously to compress air, cooling and liquefying the compressed air with the aid of the cooled, expanded inert gaseous diluent, separating the oxygen from the liquefied air and cycling it to the oxidation reaction zone to effect further oxidation of the partially oxidized hydrocarbon mixture, and cycling the cooled nitrogen separated from the liquefied air to supply necessary refrigeration to the reaction system.

10. Process for the partial oxidatiton of hydrocarbons in the vapor phase at elevated temperature and pressure to form oxygenated organic compounds, which comprises subjecting the hydrocarbons to an initial partial oxidation in a reaction zone with oxygen containing an inert gaseous diluent at a temperature of 600 to 900° F. and a pressure of 75 to 200 pounds per square inch gauge, subjecting the gaseous reaction mixture obtained to further oxidatiton with added oxygen free of any inert diluent, said further oxidation producing a temperature of 900 to 1200° F. whereby both a partial cracking of unreacted hydrocarbons present and the formation of additional oxygenated organic compounds is effected, separating the oxygenated organic compounds from the reaction gases, separating the unreacted light hydrocarbons from the inert gaseous diluent present by absorption under a pressure of 600 to 1200 pounds per square inch gauge with the aid of a liquid solvent, expanding the unabsorbed inert gaseous diluent to lower the temperature of the same and simultaneously to compress air, cooling and liquefying the compressed air with the aid of the cooled, expanded inert gaseous diluent, separating the oxygen from the liquefied air and cycling it to the oxidation reaction zone to effect further oxidation of the partially oxidized hydrocarbon mixture and cycling the cooled nitrogen separated from the liquefied air to supply necessary refrigeration to the reaction system.
